AIRSHIP

Alex A. Rommel, 4426 Brentwood Drive, Fresno, Calif.

Filed Jan. 11, 1960, Ser. No. 59,005

Term of patent 14 years

(Cl. D71—1)

FIG. 1.

FIG. 2.

FIG. 3.

Fig. 1 is a top plan view of an airship showing my new design.

Fig. 2 is a side elevation thereof. The opposite side of the airship from that shown is the same in appearance as the side shown.

Fig. 3 is a front elevation of the airship.

I claim:

The ornamental design for an airship, as shown and described.
